DESIGN FOR A MATCH BOOK HOLDER

Stephen H. Brooks and Margaret A. Wright,
Beverly Hills, Calif.

Application February 11, 1943, Serial No. 109,531

Term of patent 14 years

To all whom it may concern:

Be it known that we, Stephen H. Brooks and Margaret A. Wright, residing at 705 North Camden Drive, Beverly Hills, in the county of Los Angeles and State of California, have invented a new, original, and ornamental Design for Match Book Holders, of which the following is a specification, reference being had to the accompanying drawing, forming part thereof.

Fig. 1 is a front elevational view of a match book holder showing our new design.

Fig. 2 is a rear elevation.

Fig. 3 is a side elevation.

Fig. 4 is a lengthwise section in the direction of the arrow associated with line 4—4 of Fig. 2.

Fig. 5 is a transverse section in the direction of the arrow associated with line 5—5 of Fig. 2.

We claim:

The ornamental design for a match book holder, as shown.

STEPHEN H. BROOKS.
MARGARET A. WRIGHT.
